CONVERSION OF HYDROCARBON OILS

Richard F. Trow, Tuckahoe, N. Y., assignor, by
mesne assignments, to Texaco Development
Corporation, New York, N. Y., a corporation
of Delaware

Application September 19, 1938, Serial No. 230,539

4 Claims. (Cl. 196—9)

This invention relates to the conversion of hydrocarbon oils and has to do more particularly with a combination crude distillation and cracking unit utilizing the principle of gas reversion.

5 It is an object of the invention to segregate the virgin and cyclic or refractory stocks and to convert the refractory stocks in the presence of normally gaseous hydrocarbons to obtain gas reversion.

10 In accordance with the invention, a suitable charging stock such as crude petroleum is subjected to distillation to obtain products, including straight run gasoline, kerosene, virgin gas oil and crude residuum. The virgin gas oil is subjected 15 to independently controlled conversion conditions to obtain the desired conversion into gasoline, normally gaseous hydrocarbons, cracked gas oil and cracked residuum. The cracked residuum is flash distilled to produce a cycle gas oil which is 20 combined with the crude residuum and the mixture of crude residuum and cycle gas oil, and the cracked gas oil, are each subjected to independently controlled conversion conditions in the presence of normally gaseous hydrocarbons to effect conversion of the oils and gases into lower 25 boiling products, such as gasoline.

A virgin cracking stock may be successfully converted and optimum conditions of time, temperature and pressure conveniently obtained in 30 the absence of added normally gaseous hydrocarbons, ordinarily employed in gas reversion. On the other hand, it has been found that gas reversion may be more advantageously employed in the conversion of the cyclic or refractory stocks, 35 wherein time, pressure and temperature conditions optimum for conversion are more difficult to obtain without excessive tar and coke formation.

The cracking of a mixture of crude residuum, 40 cycle gas oil, and normally gaseous hydrocarbons is advantageous because the latter two components serve as refractory diluents and permit the maximum conversion of the less refractory crude residuum without exceeding the maximum 45 allowable overall crack per pass. The presence of the normally gaseous hydrocarbons has another effect in that the hydrocarbons enter the reaction to produce a higher gasoline yield and minimize the formation of cyclic tars. The presence 50 of the normally gaseous hydrocarbons also contributes toward ease in control of the proper degree of vaporization without the necessity of maintaining excessively high temperature levels.

The invention will be more fully understood 55 from the following description read in connec-

tion with the accompanying drawing which shows a diagrammatic sketch of one form of apparatus for carrying out the process of the invention.

A charging stock, such as crude petroleum, is introduced through the line 1 and forced by the pump 2 through a heating coil 3 wherein the oil is preheated to sufficient temperature to effect distillation of gasoline, kerosene and a major portion of the gas oil. The preheated oil is passed through line 4 to the lower portion of fractionator 5 which is maintained under atmospheric pressure. Vapors separating in the fractionator pass upward therethrough and are fractionated, the uncondensed vapors of straight run gasoline passing out from the top of the fractionator through line 8, the kerosene condensing to form a side stream which is drawn off through the line 9, and a light gas oil fraction collecting on the tray 10.

The crude residuum remaining in the lower portion of the fractionator 5 is withdrawn through the line 12 and forced by the pump 13 through a heating coil 15 wherein the residuum is further preheated under vacuum and the hot products transferred through the line 16 to an evaporator 17 in which a vacuum is maintained.

Further vaporization of the oil takes place in the vacuum tower 17. The remainder of the gas oil is separated as vapors which are removed from the top of the evaporator through the vapor line 18 and condenser 20. A heavy virgin gas oil distillate is collected in the receiver 21 from which it may be withdrawn by the pump 22 and line 23. The gas oil from the tray 10 in the fractionator 5 is withdrawn by the pump 25 through the line 26 which merges with the line 23, whereby the gas oils, both from the atmospheric tower 5 and the vacuum tower 17 are combined and pass through the line 28 to a preheater coil 30 located in an evaporator 31, referred to hereinafter. The preheated virgin gas oil is then passed through the line 32 to a heating coil 35 wherein it is raised to a cracking temperature of about 900° to 1000° F. and the hot products then transferred through the line 36 to a soaker 38, which is maintained under a pressure of about 750 pounds per square inch. The products pass upwardly through the soaker 38 wherein conversion takes place and the cracked products are thereafter transferred through the line 40 to the evaporator 31. The evaporator 31 is maintained under a pressure, for example about 200 to 250 pounds per square inch.

In the evaporator 31 the cracked products separate into vapors and residuum, the vapors passing overhead through vapor line 42 to a fractionator 55

45. In the fractionator 45 hydrocarbons of higher boiling point than the desired gasoline are condensed to form a reflux condensate or recycle stock which collects in the lower portion of the 5 fractionator from which it is withdrawn by the pump 66 and forced through the line 49 to a recycle or cracked gas oil heater 50. In the heater 50 the clean cracked gas oil is heated to a temperature of around 900° to 1100° F. and the hot 10 products then transferred through the line 51 to a soaker 52 which is maintained under a pressure of about 250 pounds per square inch, or higher, wherein sufficient time is provided for conversion to take place. The cracked products are then 15 transferred through the lines 54 and 49 to the evaporator 31.

The cracked residuum is withdrawn from the lower portion of the evaporator 31 and passed 20 through the line 55 to the lower portion of the tar stripper 56. The tar stripper is maintained under reduced pressure, for example atmospheric or slightly above, for example 15 pounds or less. The residuum is flash distilled in the tar stripper and the vapors of the more volatile constituents 25 pass into the upper portion of the tar stripper, wherein the heavier vapors are condensed to produce a cycle gas oil which collects on the tray 58. The uncondensed vapors pass overhead from the tower 56 through the vapor line 60 30 and condenser 61 to a receiver 62, wherein a gasoline fraction is collected. A heavy cracked fuel oil is withdrawn from the bottom of the tar stripper 56 through the line 66.

The heavy crude bottoms collecting in the 35 lower portion of the vacuum tower 17 are withdrawn therefrom through the line 68 in which is located a pump 70. Any portion or all of the bottoms may be passed through the branch line 71 and introduced into the upper portion of the tar stripper 56 through either or both of the manifold lines 73 and 74. If desired, any portion or all of the heavy crude bottoms may be passed through the branch line 75. The cycle 40 gas oil is withdrawn from the tar stripper 56 through the line 76 and in mixture with the crude bottoms, discharged through the branch line 71 or the branch line 75, forced by the pump 78 through the line 79 to a heating coil 80, wherein the oil is raised to a cracking temperature of about 850° to 1000° F. and the hot 45 products transferred through the line 81 to the soaker 52.

The gasoline fraction collected in the receiver 62 is withdrawn therefrom by the pump 83 and 50 passed through the line 84 to the fractionator 45, wherein the gasoline is introduced at the desired level through branch lines 85 or 86, to serve as a reflux medium. A portion of the gasoline line from the line 84 may be passed through the branch line 87 to the upper portion of the tar stripper 56 to act as a reflux medium.

The uncondensed vapors in the fractionator 45, comprising gasoline and normally gaseous hydrocarbons, are withdrawn from the upper portion of the fractionator 45 through the vapor line 88 and condenser 89 to a receiver 90. The unstabilized cracked gasoline collected in the receiver 90 is withdrawn through the line 91 by the pump 92. A portion of this gasoline may be passed through the branch line 93 and line 85 to the upper portion of fractionator 45 as a reflux medium. The remainder of the unstable cracked gasoline is conducted through the line 94 to a stabilizer 95, wherein stabilization takes 55 place, and a stabilized gasoline is withdrawn

from the lower portion of the stabilizer through the line 96. The stabilizer overhead, comprising principally C₃ and C₄ hydrocarbons, is withdrawn from the upper portion of the stabilizer through the line 98 and condenser 99 to a receiver 100. 5 A portion of the stabilizer overhead is recycled by the pump 102 through the line 103 to the upper portion of the stabilizer 95 as a reflux medium. The remainder of the stabilizer overhead is forced through the line 105 and introduced into either heater coil 80 or the heater coil 58, or both, through the branch lines 106 and 107. The stabilizer overhead so introduced into the heaters is converted into normally liquid hydrocarbons in admixture with the oil undergoing cracking therein. 10 15

The uncondensed gases and vapors in the receiver 93 are passed through the line 109 to an absorber 110 which may be operated under a pressure of about 200 pounds. Also normally 20 gaseous hydrocarbons from the receiver 62 are passed through the line 112 by the pump 113 to the absorber 110. Any portion or all of the heavy recycle gas oil withdrawn from the tray 58 of the tar stripper 56 may be passed through the 25 line 76, pump 78 and line 115 to the upper portion of the absorber 110 to act as an absorption medium. The absorption medium may contain any portion or all of the heavy crude bottoms withdrawn from evaporator 17 through the lines 30 68 and 71. It is preferable to pass the heavy crude bottoms directly through the lines 68, 75 and 79, directly to the heating coil 80 and use only the recycle gas oil collecting on the tray 58 of the tar stripper 56 as an absorption medium 35 in the absorber 110. In the absorber the gas oil scrubs out the heavier constituents, such as hydrocarbons between 2 and 5 carbon atoms, from the gases, thereby becoming enriched. The unabsorbed gases are released from the top of the 40 absorber by the line 117 while the enriched absorbent oil is withdrawn from the bottom of the absorber by the pump 118 and forced through the line 119 to the preheating coil 120, located in the upper portion of the fractionator 45 and 45 thence through the line 121 to the heating coil 80. The normally gaseous hydrocarbons absorbed in the cycle gas oil undergo conversion in the presence of the normally liquid hydrocarbons in the conversion operation. 50

Ordinarily the process herein described is self-contained, that is, sufficient normally gaseous hydrocarbons are produced in the system to effect the desired gas reversion. However, in case additional normally gaseous hydrocarbons 55 are desired, a further supply of hydrocarbons, such as propane, butane, or a mixture of propane and butane, may be introduced through the line 124 and pump 125.

As an example of the operation of the invention, an East Texas crude petroleum is preheated to a temperature of about 600° F. and subjected to atmospheric distillation to remove the straight run gasoline, kerosene and virgin gas oil. The products are further distilled under vacuum to 65 separate an additional quantity of virgin gas oil leaving fuel oil bottoms of about 17° A. P. I. gravity. The combined virgin gas oils, having a gravity of about 32° A. P. I. are heated to a temperature of about 930° F. and subjected to conversion in a soaker under a pressure of about 750 pounds per square inch. The reaction products are introduced into an evaporator operating under a pressure of about 230 pounds per square inch, wherein separation between vapors and 70 75

pressure tar occurs. The vapors are fractionated to produce a clean recycle stock which is heated to a temperature of about 960° F. and introduced into a soaker which is maintained under a temperature of about 910° F. and a pressure of about 250 pounds. The cracked products from the soaker are passed into the evaporator mentioned above. The pressure tar is subjected to flash distillation to produce a tar stripper or cycle gas oil of about 20° A. P. I. gravity which is used as an absorption medium for absorbing the heavier constituents of the normally gaseous hydrocarbons produced in the system. A mixture of the enriched cycle gas oil and heavy crude bottoms of about 17° A. P. I. gravity, referred to heretofore, is heated to about 900° F. in a black oil heater and the hot products discharged into the aforementioned soaker, receiving the products from the clean oil heater. An unstable cracked gasoline is recovered and subjected to stabilization and the stabilizer reflux is introduced into the black oil and clean oil heaters. The normally gaseous hydrocarbons introduced into these heaters amount to about 68% of the total charge to the heaters. A yield of gasoline, based on the crude, of about 70% with an octane number of about 70 is obtained.

Obviously many modifications and variations of the invention, as hereinbefore set forth, may be made without departing from the spirit and scope thereof, and therefore only such limitations should be imposed as are indicated in the appended claims.

I claim:

1. A process for the conversion of hydrocarbon oils which comprises distilling a crude petroleum in the absence of substantially any cracked products to produce a reduced crude

and virgin gas oil, subjecting said virgin gas oil substantially free from refractory cracked materials to a once-through cracking operation, separating the cracked products into vapors and residuum, flash distilling the residuum to produce a cycle gas oil, subjecting a mixture of said cycle gas oil and said reduced crude to separate cracking in the presence of normally gaseous hydrocarbons under reversion conditions in a coil and soaker, separating the cracked products from the soaker into vapors and residuum, subjecting the last mentioned residuum to the flash distillation operation in which said first mentioned residuum is flash distilled, fractionating the vapors from both of said cracking operations to recover a clean recycle stock, subjecting said recycle stock to cracking in a separate coil, discharging the cracked products from the last mentioned coil into said soaker to undergo soaking together with the cracked mixture of said crude residuum, cycle gas oil and normally gaseous hydrocarbons, and recovering gasoline from the system. 10

2. A process according to claim 1 in which the cracked products from the virgin gas oil cracking operation and the cracked products from said soaking operation are passed to a common separator. 25

3. A process according to claim 1 in which the clean recycle stock is cracked both in the coil and in the soaker in the presence of normally gaseous hydrocarbons under gas reversion conditions. 30

4. A process according to claim 1 in which cracked gases from the system are scrubbed with the cycle gas oil and the enriched cycle gas oil treated in the gas reversion operation. 35

RICHARD F. TROW.
